UNITED STATES PATENT OFFICE.

WILLIAM H. WILKINSON, OF NEW YORK, N. Y.

DESIGN FOR A GAS-STOVE.

SPECIFICATION forming part of Design No. 26,150, dated October 6, 1896.

Application filed August 21, 1896. Serial No. 603,543. Term of patent 3½ years.

To all whom it may concern:

Be it known that I, WILLIAM H. WILKINSON, a citizen of the United States, and a resident of New York city, in the county of New York and State of New York, have invented and produced a new and original Design for Gas-Stoves; and I do hereby declare that the following is a full, clear, and exact description of the invention, which will enable others skilled in the art to which it appertains to make and use the same, reference being had to the accompanying drawing, which forms a part of this specification.

My invention relates to a design for gas-stoves; and the essential feature consists in the peculiar configuration and construction given to the same, whereby a very ornamental and attractive appearance is presented.

In the accompanying drawing, the figure 20 represents a front elevation of a gas-stove constructed according to my design.

In the said drawing the reference-numeral 1 designates the base of the stove, having legs 2 and a scalloped edge 3, and is ornamented 25 by means of scrollwork 4.

The numeral 5 designates the front of the stove, having a large central opening therein. This casing is composed of ornamental open-work, and the edge of the said opening is composed of a number of fancy scrolls 6. The 30 top 7 of the stove is ornamented by an open-work shield 7^a at the center, at each side of which are ornamental scrolls 8. Inclosed by the said casing are a number of heating-tubes 9, provided with a series of perforations 10, 35 and near each end are formed with ornamental beads or ribs 12.

What I claim is—

The design for a gas-stove herein shown and described. 40

In testimony that I claim the foregoing as my own I have hereunto affixed my signature in presence of two witnesses.

WILLIAM H. WILKINSON.
